UNITED STATES PATENT OFFICE.

EDWARD HADRA, OF CUMBERLAND, MARYLAND.

MACHINE FOR COLORING AND FLAVORING CIGARS.

SPECIFICATION forming part of Letters Patent No. 237,522, dated February 8, 1881.

Application filed December 20, 1880. (No model.)

To all whom it may concern:

Be it known that I, EDWARD HADRA, a citizen of the United States, residing at Cumberland, in the county of Allegany and State of Maryland, have invented new and useful Improvements in Machines for Coloring and Flavoring Cigars, of which the following is a specification.

The object of this invention is to apply to manufactured cigars or tobacco a suitable coloring or coloring and flavoring liquid in a rapid and effective manner and without injury to the wrappers.

It consists, mainly, in the combination, in a machine for coloring and flavoring manufactured cigars and tobacco, of a concave having a smooth inner face, and a rotary cylinder provided with a radially-yielding facing of sponge, and arranged to rotate within the concave, whereby, when the sponge facing is supplied with a coloring or coloring and flavoring liquid and manufactured cigars or tobacco are introduced between the cylinder and concave, they will be carried around with a rolling motion, forced into the sponge as they travel, and receive therefrom a thorough application of the said coloring or coloring and flavoring liquid without injury to the wrappers, as herein-after fully described.

In the drawings, Figure 1 is a perspective view of a machine embodying my invention: Fig. 2 is a top or plan view thereof with the tray removed. Fig. 3 is a section taken on a central vertical plane; and Fig. 4 is a perspective view of the tray, showing principally the bottom side thereof.

The letter A indicates the concave, which is supported upon a frame, B, of any suitable construction.

C refers to the rotary cylinder, which may be either a solid block of wood or other material. If desired, however, it may be made hollow and provided with internal spider-frames. This rotary cylinder is set up to the inner face of the concave, so that the cylinder will rotate within the latter. The face of this cylinder is covered with a layer, C', of sponge, which is tacked onto the cylinder along the edges, or otherwise suitably secured there-

to. The shaft of the cylinder is journaled in the bearings D, which, in the present instance,

consist of two horizontal bars adjustably secured to the standards E of the main frame by means of set-screws. This adjustment enables the operator to regulate the space between the concave and the rotary cylinder, so as to allow the cylinder to carry cigars of different sizes along the inner face of the concave.

The end walls, a, of the concave are formed with horizontal slots a', through which the journals of the cylinder extend, said slots admitting of the adjustment just mentioned being made.

Upon one end of the cylinder-shaft is a crank, F, whereby a rotary movement can be imparted to the cylinder, although the crank may be dispensed with, if desired, and the cylinder driven by belt-power applied to a pulley upon said shaft. These journals are also detachably mounted on their bearings, so that the same can be removed when occasion requires.

In rear of the concave, and above the rotary cylinder, is arranged a tray, H, with sides h h h, for holding tobacco or cigars. This tray rests upon suitable frame-work and inclines down toward the rotary cylinder, so as to admit of the cigars or tobacco being readily fed from the tray onto the cylinder. The lower end of this tray terminates above the cylinder just in rear of the concave, so that cigars or tobacco fed onto the cylinder will be carried round by the rotary cylinder between it and the concave, and the concave has a vertical flange, g, which prevents the cigars from passing over it. Below this tray, and above the sponge-faced rotary cylinder, is arranged a tube or trough, I, provided with perforations i in its bottom, through which the coloring and flavoring liquid drips onto the sponge facing of the cylinder. This trough may be supplied from an elevated tank, K, through a pipe, M, provided with a suitable cock for cutting off the flow of liquid from the tank to the trough after the sponge facing of the rotary cylinder has been supplied with the proper quantity of liquid.

L indicates an inclined chute, arranged below the cylinder, for the cigars or tobacco to drop upon as they come from between the cylinder and the concave. This chute may lead

to any convenient receptacle for collecting the articles after they have been treated.

Any suitable coloring or coloring and flavoring compound may be used in this machine—such, for instance, as a compound composed of the compound extract of black licorice, gum-catechu, and logwood, and this may be supplied to the sponge by the above-described tank and trough, or it may be supplied to the sponge by hand.

The operation is as follows: The sponge being properly saturated with the coloring or the coloring and flavoring compound, the cigars are fed by hand from the tray onto the sponge-faced roller, which, during its rotation, carries them round along the inner face of the concave. The cigars will be pressed into the sponge by the concave, and will, by frictional contact therewith, rotate sufficiently to expose their entire outer surface to the sponge, thus insuring an equal distribution of the coloring and flavoring compound over the cigars. After the cigars have passed the concave they drop down upon the chute, which conducts them to the desired receptacle.

In coloring plug-tobacco the cylinder and concave should be made longer than for cigars, the rotary cylinder being set at the required distance from the concave by adjusting its bearings.

It is evident that a variety of forms of framework for supporting the operative parts of this machine can be employed, and that also other means than those herein shown can be employed for regulating the space between the sponge facing of the rotary cylinder and the concave.

In some instances it may be desirable to remove the rotary cylinder and wrap it up during the non-usage of the machine, in order to prevent the sponge from becoming hard and dry, and this will be readily effected by adjusting the bearings of the cylinder-journals and removing the said journals from their bearings. Cigars or tobacco can be colored and flavored very rapidly in this way, since

the sponge will absorb a large quantity of the compound employed. In place of sponge, any fibrous or textile material may be used which will absorb a sufficient quantity of the coloring and flavoring compound and transmit the same to the surface of the cigars or tobacco, although I deem the sponge facing of the rotary cylinder to be the best.

What I claim is—

1. In a machine for coloring and flavoring manufactured cigars and tobacco, the combination, with the concave having a smooth inner face, of the rotary cylinder provided with a radially-yielding facing of sponge for carrying a coloring or flavoring liquid, and arranged to rotate within the concave, whereby, while the cigars or tobacco are carried around between the cylinder and concave, they will be forced into the yielding facing of the cylinder and become stained or flavored, or both, by the liquid held by the sponge, being subjected to a rolling and not a brushing action.

2. In a machine for coloring and flavoring cigars and tobacco, the combination, with the concave, of a rotary cylinder provided with a sponge facing, and a perforated trough for supplying the coloring and flavoring liquid to the sponge, substantially as described.

3. In a machine for coloring and flavoring manufactured cigars and tobacco, the combination of a concave having a smooth inner face, a rotary cylinder provided with a radially-yielding facing of sponge for carrying a coloring or flavoring liquid, and horizontal bars adjustably secured to the standards of the main frame by set-screws, and provided with bearings in which the cylinder is journaled, all substantially as and for the purpose described.

In testimony whereof I have hereunto set my hand in the presence of two subscribing witnesses.

EDWARD HADRA.

Witnesses:

JAMES L. NORRIS,
JAMES A. RUTHERFORD.
